CLAIM

The ornamental design for a nozzle body and a housing for a hand spray gun, substantially as shown and described.

DESCRIPTION

FIG. 1 is a perspective view of a hand spray gun showing our new design;

FIG. 2 is a side elevation view thereof;

FIG. 3 is a front elevation view thereof;

FIG. 4 is a back elevation view thereof;

FIG. 5 is a top plan view thereof; and

FIG. 6 is a bottom plan view thereof.
